UNITED STATES PATENT OFFICE.

JOSEPH S. STRING, OF NEW HAVEN, CONNECTICUT, ASSIGNOR TO J. S. & J. F. STRING INCORPORATED, OF NEW HAVEN, CONNECTICUT, A CORPORATION OF CONNECTICUT.

LIQUID-FUEL BURNER.

Application filed June 24, 1924. Serial No. 721,986.

My invention relates to that type of hydrocarbon burners in which the fuel is exteriorly atomized by means of air or steam or any other expansive fluid.

5 The principal object of the invention is the production of a hydrocarbon burner of the type specified in which the size of the discharge opening for the expansive fluid may be quickly contracted or enlarged to 10 meet varying conditions whereupon the size of the flame resulting from the combustion of the atomized fuel may be expeditiously increased or decreased as desired.

A further object of the invention is the 15 production of a burner of the type specified in which the width and length of the discharge opening for the expansive fluid may be simultaneously increased or decreased to increase or decrease the volume of the expansive fluid depending on the amount of fuel to be burned, without however, altering the angularity of the horizontal spread of the fuel.

Other and further objects and advantages 25 of the invention will appear from the accompanying description, the invention consisting in the novel burner and parts and combinations thereof hereinafter more particularly described and then specified in the 30 claims.

Referring to the accompanying drawing illustrating a practical embodiment of my invention:

Fig. 1 is a side elevation of my improved 35 hydrocarbon burner.

Fig. 2 is a longitudinal section taken therethrough.

Fig. 3 is a bottom plan view thereof and Fig. 4 is an end elevation thereof.

40 Referring to the accompanying drawings in which like characters of reference indicate corresponding parts in all the views:

1 indicates the body of the burner, said body being provided with a fuel passageway 2 adapted to be connected at its rear end 3 by a pipe (not shown) with a source of fuel supply such as oil. Said body is also provided with an inner chamber 4 which receives an expansive fluid such as air or steam through a pipe (not shown) adapted to be connected to a source of expansive fluid supply and to the inlet opening 5 of

said chamber. The body 1 is preferably provided with a rearwardly-extending, interiorly screw-threaded extension 6 receiving 55 a screw-threaded stem 7 extending therethrough, said screw-threaded stem 7 being interiorly screw-threaded as at 8 and receiving a screw-threaded spindle 9. The threads of the stem 7 are preferably right-handed, 60 while those of the spindle 9 are left-handed or vice-versa. The stem 7 is provided with a collar 10 acting as a stop to limit the forward threading movement of said stem in the extension 6, the right or unthreaded portion of said stem which I have designated 11, being provided with an operating arm or handle 12.

The forward end of the body of the burner is provided with an opening 13 having 70 side walls 14 extending forwardly from said body. Seated on said side walls and detachably secured to the forward face of the body adjacent the outlet of the fuel passageway 2 is a detachable cap 15 provided 75 with a fuel receiving chamber 16 and with a slot 17 whereby the fuel will flow through the passageway 2 into the fuel receiving chamber 16, through the slot 17 and to the opening 13. It will be noted that the fuel receiving passageway 2 is inclined rearwardly so that when the burner is not functioning any excess oil in said passageway will flow back therethrough into the source of fuel supply thereby preventing waste thereof. The base of the cap 15 is provided with a groove 18 centrally disposed thereof, the sides of which groove preferably flare or are inclined outwardly as clearly shown in Fig. 3, so that when the oil flows through the slot 17 and is atomized by the atomizing fluid, it will be given a flat fan-shaped spread or direction.

Rotatably mounted in suitable depressions or seats provided in the opposite walls of the chamber 4 are the discs or annular side walls 19 of a drum 20 the body of which is provided with an enlarged inlet opening 21 communicating with the chamber 4 and with a somewhat smaller discharge opening 22 adapted to communicate with the opening 13.

The side walls of the discharge opening 22 of the drum are tapered or are inclined

outwardly as shown in Fig. 4, so that the length of the opening as well as the width thereof simultaneously increases proportional to the amount of rotation given the drum 5 in a clockwise direction.

The inner end of the spindle 9 is provided with a slotted member 23 to which is pivoted, by a pin 24, the shank 25 of a fork 26, the forward end of said fork being loosely mounted on a pin 27 the ends of which are secured to the annular side walls 19 of the drum 20. The point of connection of the ends of said pin 27 with the side walls 19 is considerably off center as respects said side walls, as clearly shown in Fig. 2.

To rotate the drum 20 whereby communication may be had between the chamber 4 and the opening 13 through the opening 21 and discharge opening 22, a mere turning 20 of the handle 12 is necessary as is obvious, the fact that the stem 7 and spindle 9 are oppositely threaded acting to produce a quick motion of the fork 26 and in consequence a quick rotation of the drum.

25 When fuel is forced through the passageway 2 it enters the chamber 16, passes through the slot 17 and is atomized by the expansive fluid which is forced through the inlet opening 5 into the chamber 4 and through the inlet and outlet openings 21 and 22 respectively of the drum. It is then ignited by any suitable flame (not shown.) When the fuel leaves the slot 17 it is spread out by the expansive fluid in a fan-shaped 30 direction by the groove 18 which acts as a guide therefor. To meet varying conditions the thickness of the flame may be regulated by rotation of the drum whereby the size of the outlet opening 22 is varied and in consequence the amount of expansive fluid which may be forced therethrough. However, irrespective of the increase or decrease of the size of the outlet opening 22 and the consequent variation in the thickness of the 40 flame, the angularity of the horizontal spread of the fuel is not varied for the reason that when the length of the opening 22 is increased or decreased the width thereof is simultaneously increased or decreased because of the inclination of the side walls of 45 said opening.

Various modifications may be resorted to without departing from the spirit of the invention as set forth in the appended claims.

55 What I claim as my invention is:

1. A hydrocarbon burner provided with a fuel passageway and with an atomizing fluid chamber, a rotatable hollow drum mounted in said chamber and provided with an inlet opening communicating with said chamber and with an outlet opening through which the fluid passes into a space adjacent the fuel passageway outlet.

60 2. A hydrocarbon burner provided with a fuel passageway having an outlet opening,

said burner being provided with a fan-shaped groove adjacent said opening and an atomizing fluid passageway in said burner having an outlet opening adjacent said fan-shaped groove and adapted to be varied in 70 length and width independently of the fuel passage outlet.

3. A hydrocarbon burner provided with a fuel passageway and an atomizing fluid chamber, a rotatable drum mounted in said chamber and provided with an outlet opening the length and width of which may be simultaneously increased or diminished and a fuel passageway outlet adjacent said outlet opening.

4. A hydrocarbon burner comprising a body provided with a fuel passageway, an atomizing fluid chamber and an opening communicating with said atomizing fluid chamber and a rotatable member in said chamber provided with an inlet opening communicating with said chamber and an outlet opening adapted to communicate with the opening in said body and having length and width simultaneously increased or diminished by rotation of the rotatable member and a fuel passageway outlet adjacent said outlet opening.

5. A hydrocarbon burner comprising a body having a walled opening therein, a fuel passageway in said body, an atomizing fluid chamber communicating with said opening adjacent the fuel passageway outlet, a detachable cap seated on the walls of said opening and detachably secured to said body adjacent said fuel passageway, said cap being provided with a fuel chamber and with an outlet opening therefrom into a flaring groove in the lower edge of the cap over the opening in said body.

6. A hydrocarbon burner comprising a body provided with a fuel passageway and with an atomizing fluid chamber, a rotatable member mounted in said fluid chamber and adapted to have the atomizing fluid discharged therethrough, oppositely threaded members connected with said rotatable member and means whereby said oppositely threaded members may be actuated to rotate said rotatable member.

7. A hydrocarbon burner provided with a body provided with a fuel passageway, an atomizing fluid chamber, a rotatable drum mounted in said atomizing fluid chamber adapted to have the atomizing fluid discharged therethrough, a screw-threaded stem threading through said body, a screw-threaded spindle threading within an opening in said stem, a connecting member pivoted to said spindle and to said drum and means for actuating said stem to rotate said drum.

8. A hydrocarbon burner provided with a fuel passageway and with an atomizing fluid chamber, a rotatable drum provided with an

nular side walls rotatably mounted in the side walls of said chamber and with inlet and outlet openings through which the atomizing fluid is adapted to be discharged, oppositely threaded members mounted in said body, means connecting said drum and said oppositely threaded members and means for

actuating said oppositely threaded members to produce rotation of said drum.

Signed at New York in the county of New York and State of New York this 23rd day of June A. D. 1924.

JOSEPH S. STRING.
